UNITED STATES PATENT OFFICE.

BARTHOLOMEW VALLETT, OF PROVIDENCE, RHODE ISLAND.

CABINET FOR CURTAINS.

SPECIFICATION forming part of Letters Patent No. 330,645, dated November 17, 1885.

Application filed September 10, 1884. Serial No. 142,567. (No model.)

To all whom it may concern:

Be it known that I, BARTHOLOMEW VALLETT, a citizen of the United States, residing at Providence, in the county of Providence and State of Rhode Island, have invented certain new and useful Improvements in Cabinets for Curtains, &c.; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

15 My invention relates to cabinets used for exhibiting curtains, maps, charts, &c.; and it consists, essentially, of a pivoted or hinged frame upon which the curtains, &c., are mounted, in combination with a case or housing having pivoted therein the curtain-carrying frame.

The invention further consists of a cabinet having an outer case and an inner pivoted frame, the latter adapted to carry the curtains, &c., and also being provided with means for 25 lowering or swinging the free end of the frame from the casing, whereby the curtains, &c., are readily adapted to be unrolled and inspected, and means for returning said frame within the casing, the whole being then covered with a screen or guard, all as will be 30 more fully hereinafter set forth.

In my improved cabinet the curtains or other articles are mounted upon a frame pivoted to the lower end of a casing, which in turn is 35 adapted to be secured to a wall or partition, a cover or screen serving to exclude dust and light when closed.

40 My device is equally well adapted to be used in halls, offices, or other places, for the purpose of holding maps, charts, &c.

In the accompanying sheet of drawings, Figure 1 represents a perspective view of the cabinet complete, the curtains, however, being removed, and the pivoted frame shown as 45 raised or closed. Fig. 2 represents an enlarged cross-sectional view of the cabinet secured to a wall, the swinging frame with its contents being shown in position for use. Fig. 3 represents a side elevation of the same when closed and 50 protected by the screen; and Fig. 4 represents a sectional view of a modification of the device, wherein a recess in the wall serves the pur-

pose of the casing, the top of the frame being swung past the center of the pivot.

The following is a description of the invention and the manner of its operation.

A designates the cabinet as a whole when provided with the housing or case B, made of wood or other suitable material, and adapted to be secured to a wall by means of brackets t.

C designates two sides of the swinging frame or holder mounted within said case, and pivoted thereto near its lower end by means of the rod s. A rod, s', serves to rigidly tie the upper end of the frame together. Chains e, or 65 other equivalent means connecting said case and frame, serve to limit the angular movement of said frame. Cords o, o', attached to the tie s', in connection with pulleys h h', secured, respectively, to the top and bottom of 70 the case, inside thereof, serve as means for operating the frame. A screen or curtain, D, at the top of the cabinet is used to exclude dust and light from the interior when closed, the guard d being employed to protect the 75 curtain.

n n represent fixtures secured to the inner faces of the frame C, within which are mounted the curtains m or other analogous articles.

The following is its operation: Assuming 80 the cabinet to be mounted and secured to a wall or partition, as shown in Fig. 3, the screen D is first rolled up, after which the operator grasps the two cords o, o', when, by pulling upon the former and at the same time slackening the latter cord, the frame C, with its contents, is lowered (if desired) to its limit, the chains e retaining it in place, (see Fig. 2,) after which any or all of the curtains m may be successively drawn down for inspection. 85 To close the frame C, the curtains m are first rolled up, when, by pulling upon the lower cord, o, said frame is carried within the case, the top of the frame passing inside the line of the pivot or the center s, (see Fig. 4, and also 95 Fig. 2, dotted lines,) thereby preventing the frame from being accidentally lowered, and relieving the said cord o from undue tension. The curtain D may now be lowered.

It is obvious that a counter-weight or a spring 100 even may be employed in lieu of the lower cord, o, for the purpose of returning the frame C. The lower pulley, h', may be cam-shaped, thus serving, in connection with the cord, to

adjustably limit the movement of the hinged frame. It is also evident that hinged or jointed links can be used instead of the chains *e*, the same to be secured to the sides of the case *B* 5 and frame *C*.

My improved cabinet is also adapted to display a series of small articles, the same to be attached to rods extending across the frame.

I do not claim a cabinet or stand having one 10 or more stationary or angular sides adapted to hold curtains, &c; neither do I claim, broadly, a hinged or folding rack, as such cabinets have been in use prior to my invention; but

15 What I do claim, and desire to secure by Letters Patent, is—

1. In a cabinet for exhibiting curtains, &c., the frame or holder *C*, in combination with the case *B*, having said frame pivoted thereto, 20 flexible connections *e*, uniting said frame and case, and means, substantially as described, for operating the holder, as and for the purpose hereinbefore set forth.

2. The cabinet *A*, for exhibiting curtains,

&c., herein described, consisting of the casing 25 *B*, having the exterior guard or screen, *D*, connected therewith, the holder or frame *C*, pivoted to said casing, means, substantially as shown, for operating the frame, consisting of the flexible connections *e* and cords *o' o*, 30 the latter mounted in suitable sheaves or pulleys, the whole combined, arranged, and adapted for use, substantially as shown and set forth.

3. The combination, with casing *B*, provided with a screen, *D*, of the pivoted frame *C*, provided with upper and lower operating-cords, *o' o*, and suitable sheaves or pulleys for the same, whereby said frame is adapted to be swung or lowered to any desired position, all 40 substantially as shown and set forth.

In testimony whereof I have affixed my signature in presence of two witnesses.

BARTHOLOMEW VALLETT.
